[57] **CLAIM**

The ornamental design for a prosthetic brace, as shown and described.

DESCRIPTION

FIG. 1 is a right side view of a prosthetic brace constructed in accordance with a preferred embodiment of the invention;

FIG. 2 is a front view thereof;

FIG. 3 is a rear view thereof;

FIG. 4 is a left side view thereof;

FIG. 5 is a bottom view thereof; and,

FIG. 6 is a top view thereof.

The prosthetic brace is hollow with a substantially uniform wall thickness throughout.
